UNITED STATES PATENT OFFICE

CARL E. KLEIN, OF WILLOW GROVE, PENNSYLVANIA

COUNTERBALANCE FOR STOVE DOORS

Application filed February 6, 1930. Serial No. 426,382.

This invention relates to a device for maintaining a door of a stove in closed position and tending to close the door when the door is open.

5 An object of the invention is the provision of a device for maintaining a door closed or tending to close the door when it is open in which a lever pivotally mounted intermediate its ends is held in a predetermined position 10 for forcing an arm of the door by means of a link downwardly so that the arm will force the door into a closed position.

A further object of the invention is the provision of a door having depending arms 15 which are curved outwardly and then inwardly and connected by means of links to levers which are pivotally mounted on the side walls of the oven, a weight or spring being co-operatively associated with the free 20 end of each lever tending to move the arm to a position where it will force the door to its closed operative position.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a fragmentary view in elevation 35 of the rear of a stove door showing my invention applied thereto.

Figure 2 is a vertical section showing the parts in an operative position for maintaining the door closed.

40 Figure 3 is a similar section showing a slightly modified form of the invention.

Figure 4 is a vertical section of a modified form of the device for maintaining the stove door closed.

45 Figure 5 is a vertical section of a further modified form of the invention.

Figure 6 is a vertical section of a still further modification of the invention.

Referring more particularly to the drawings, 50 10 designates a stove having a door

frame 11 mounted at the front across the lower end of which is extended a bar 12. A curved portion 13 is formed at the upper inner edge of the bar to provide a rest as will be presently explained.

Curved arms 14 extend from the lower edge of a door 15 and are formed with curved seats which rest upon the curved portion 13 of the bar 12. Each arm, as shown at 16, is extended downwardly, then curved outwardly, as at 17, and then inwardly, as at 18.

A link 20 has one end pivoted upon a rod 19 which is carried by bearings in the free ends 18 of the arms 14. The other end of the link is connected to the outer end of a lever 25 pivoted at 26, upon an opposite side wall 27 of the stove.

The free end of the lever 25 is provided with a link 29 which receives the lower ends of springs 30 which are secured, at 31, to a side wall of a stove. The springs may be enclosed within casings formed in the oven or they may be mounted exteriorly of the stove.

The operation of the device shown in Figs. 1 and 2 is as follows: When the door 15 is moved outwardly the curved portion 14 swings upon the curved portion 13 and the bar 12, these members thereby acting as a hinge for the door. As the door swings outwardly the free ends 18 of the arms 14 move upwardly until they reach the stop 50. The links 20 are likewise carried upwardly and moved toward a horizontal position while the inner end of the lever 25 is moved above the horizontal plane and at an angle to the normal horizontal position of the lever 25. The opposite end of the lever is moved downwardly against the tension of the springs 30.

When the door is released the springs will move the lever 25 to its normal inoperative position and cause the link 20 to move the arm 14 to the position shown in Fig. 2 whence the spring will aid in maintaining the door closed.

The modified form shown in Fig. 3 contains all the essential elements of the structure disclosed in Fig. 2 except that a weight 49 is employed instead of the springs 30. The lever 40 is pivoted at 41 upon the side 100

wall 27 of the stove 10 and has one end 42 pivotally connected with the upper end of the link 20.

The opposite end of the lever is slotted, 5 at 43, to receive a pin 44 which also rides in a slot 45 of a lever 47. This lever is pivoted at 48 upon a side wall of the stove. This construction also includes a link 40 and a pair of levers 40 and 47 upon the opposite 10 side walls of the stove.

The operation of the device shown in Fig. 3 is as follows: The door 15 is moved outwardly from the frame 11 so that the curved portion of the arm 14 will ride over 15 the curved seat of the bar 12, thereby causing the portion 17 of the arm, the link 20, the levers 40 and 47, to be moved to the dotted line position so that the weight 49 will be elevating tending to close the door 15 at all 20 times and for maintaining the door in snug relation with the outer face of the frame 11.

Referring more particularly to Fig. 4 it will be seen that a modified form of the invention is disclosed in which links 55 are 25 mounted upon a rod 56 carried by the curved arms 57 formed at the bottom of the door 58, which normally is in operative position within a frame 59 of the door of the stove 60. A lever 61 is pivoted at 62 on a side wall of 30 the stove, while the opposite end is pivoted at 63 to the free end of the link 55.

A lever 64 is pivoted at 65 on a side wall of the stove 60 and a link 66 connects the lever 64 with the lever 61, as shown at 67 35 and 68. A weight 69 is secured to the outer free end of the lever 64.

The operation of the device shown in Fig. 4 is as follows: The door 58 rests upon a seat 70 formed at the upper end of the 40 bracket 71 and is adapted to swing on said seat to an open position. When the door is moved downwardly the link 55 is moved inwardly and upwardly, thereby raising the levers 61 and 64 and the weight 69 so that 45 the weight will tend to close the door when it is opened. When the door is released, weight 69 will descend, thereby moving the levers 61 and 64 to the position shown in Fig. 4.

50 In the modification disclosed in Fig. 5 the door 72 is mounted for swinging movement on the member 73 and a pair of links 74 are connected to the downwardly projecting arms 75 formed at the bottom of the door 72. This 55 link is connected at 76 with the outer end of a lever 77, which is pivoted at 78 to a side wall of the stove 79. A plurality of springs 80 are connected at 81 to the lever 77 adjacent the pivotal connection between said lever and the 60 link 74. The opposite ends of the spring are secured at 82 to a side wall of the stove. The links 74, as disclosed in the other forms, are pivotally mounted upon a rod 83 carried by the downwardly projecting arm 75.

65 When the bar 72 is moved outwardly the

arms 75 move upwardly, forcing the links 74 inwardly and upwardly, thereby leaving the outer end of the lever 77 against the tension of the springs 80. These springs tend at all times to close the door so that when said door is released the lever 77 will be pulled downwardly by said springs and move the door into snug engagement with the outer wall of the frame 84 which embraces the opening at the front of the stove. 75

Another modified form of the invention is disclosed in Fig. 6, and the door 85 is mounted for swinging movement on a support 86 which is similar in construction to the form described above. Arms 87 project downwardly from opposite ends of the bottom portion of the door and carry a rod 88 which extends across the bottom of the door in a manner similar to the disposition of the rod 19 disclosed in Figure 1. 80

A lever 89 is pivoted at 90 on a side wall of the stove 91 and has its outer free end connected with springs 92 secured at 93 to a side wall of the stove. The outer end of the lever adjacent the door 85 is curved downwardly as 90 shown at 94, and is provided with a horizontal slot 95 to receive the rod 88.

When the door 85 is swung outwardly on its hinged portion, the arms 87 are moved inwardly and upwardly, thereby moving the rod 88 through the slot 95 and elevating the portion 95 of the lever 89. The opposite end of the lever is moved downwardly against the tension of the springs 92 for restraining downward movement of the inner free end of 100 the lever, thereby tending to move the door 85 to its closed position. When said door is released the springs will come into play for actuating the lever 89 and thus move the door in snug relation with the outer wall of 105 the frame of the door.

I claim:

1. In a stove, a door frame, a bar carried by the frame, a door having a seat to receive the bar for pivotally supporting the door, the door having a curved arm extending inwardly from the door, a lever pivotally mounted intermediate the ends and normally lying in a horizontal plane, a link connecting the free end of the arm to one end of the lever, and means connected with the other end of the lever and resisting movement of the lever, the lever and link co-operating to retain the seat of the door on the bar. 110

2. In a stove, a door frame, a bar carried by the frame, a door having a seat to receive the bar for pivotally supporting the door, a pair of arms curved outwardly and inwardly from the lower end of the door and having a free end extending beyond the confines of 120 the frame, horizontally disposed levers pivotally mounted intermediate the ends thereof on the stove, a rod carried by the arms, a link pivoted at one end on the rod, the other end of each link being pivotally connected 125 to the outer end of each arm, the link being pivotally connected 130 to the outer end of each arm.

with an end of a lever, and means restraining movement of the levers for maintaining the door in closed position, the levers and links co-operating to retain the seat of the door on the bar.

3. In a stove, a door frame, a door mounted for swinging movement on the frame, arms projecting downwardly from the lower edge of the door, a rod supported by the arms, a link pivotally mounted at one end on the rod, a lever pivotally mounted on the stove and having one end pivotally connected with the other end of the link, and means connected with the lever for restraining movement of said lever when the door is opened, and for returning the door to closed position, the lever and link co-operating to retain the seat of the door on the bar.

CARL E. KLEIN.
